Atty.

Patented May 22, 1928.

UNITED STATES PATENT OFFICE.

HUGH GRIFFITHS, OF LONDON, ENGLAND.

FIRE EXTINGUISHER.

Application filed January 14, 1926, Serial No. 81,225, and in Great Britain January 28, 1925.

This invention is for improvements in or relating to fire-extinguishers, and has for its object to provide an improved construction of device of the type in which a suitable fire-extinguishing liquid is contained in a closed vessel, usually portable, with some simply-controlled means whereby it can be expelled therefrom when required for use.

10 Among the liquids used for fire-extinguishing are some which are of a volatile nature, their effect being one of smothering the fire by means of a non-inflammable vapour, and as an instance of such liquids 15 methyl-bromide may be mentioned. The storage of such liquids, however, in closed containers involves various difficulties, and the object of the present invention is to provide a container which is suitable for use 20 with such liquids; it is to be understood, however, that the invention is not limited to the use of any particular liquid.

According to this invention, a fire-extinguishing device suitable for use with methyl-bromide and other highly volatile liquids 25 comprises a chamber which is entirely hermetically sealed but has a part of its wall so arranged as to be destructible or puncturable, in combination with means for destroying or puncturing such part to release 30 the liquid when required.

This construction renders it possible to provide containers in which the use of stop-cocks, valves or the like is avoided, and the 35 principal difficulties relating to the storing of such liquids are thereby obviated.

According to another feature of this invention, the fire-extinguisher comprises in combination two vessels, whereof one is hermetically sealed and the other is provided 40 with an outlet nozzle, the puncturable or destructible diaphragm constituting a wall common to the two vessels, and means for puncturing or destroying the diaphragm at 45 will so as to allow the liquid to pass from the normally sealed chamber into the second chamber, and thence to the outlet nozzle.

According to another feature of this invention, the means provided for puncturing 50 or destroying the diaphragm is situated entirely outside the sealed chamber so that the completeness of its sealing is not impaired; preferably the device, which may 55 comprise a pointed pin or the like, has an operating handle or head outside the fire-extinguisher and extends through the second

chamber to a point near the diaphragm to be ruptured, so that no special packing or mounting is required for it.

Some of the liquids used in fire-extinguishing devices are self-propelling insofar as their vapour pressure is sufficiently high. According to another feature of the present invention, there may be provided the combination with a fire-extinguishing device 60 constructed as above set forth, of means situated within the sealed chamber for releasing a compressed gas, or for generating a supply of gas for propelling the liquid, and means for effecting such release or generation simultaneously or automatically with the rupture of the diaphragm aforesaid. In one construction according to this arrangement, a bulb containing a supply of compressed gas such as carbon-dioxide may be 70 mounted within the sealed chamber near the puncturable diaphragm, in such a position that after the pin has been moved to puncture the diaphragm, a slight further movement causes it to pierce the closure means 80 of the bulb and release the gas into the closed chamber. The gas pressure thus applied to the liquid forces it into the second chamber and thence to the delivery nozzle of the extinguisher.

85 The accompanying drawing is a central vertical section showing one construction of fire-extinguisher in accordance with the present invention.

Referring to this drawing, the device 90 comprises a container 1 of a suitable size to contain the desired quantity of fire-extinguishing liquid. At its lower end this container is provided with an opening 2 which is closed by a thin sheet-metal dia- 95 phragm 3 which is soldered in place. The other joints in the container are all soldered so that a true hermetic closure of the vessel 1 is obtained.

A second vessel 4 providing a chamber 5 100 is secured in any convenient manner on the outside of the container 1 around the dia- phragm 3, so that this diaphragm constitutes one of the walls of the chamber 5. From this chamber 5 a delivery-pipe 6 ex- 105 tends in any convenient manner, and a suit- able nozzle 7 is provided to form a convenient jet through which the fire-extin- guishing liquid is delivered.

110 Provision is made for puncturing the dia- phragm 3, and in the construction illustrated there is provided a pin 8 which is mounted

to slide in a suitable guide 9, mounted in the wall of the chamber 4, towards the diaphragm 3. A head or cap 10 is provided on the outer exposed end of the pin 8 to facilitate its manipulation. The pin 8 is so positioned and is of such a length that when it is driven inwards, its pointed end 11 punctures the diaphragm 3 and thereby provides communication from the interior of the vessel 1 to the chamber 5. Any liquid contained in the vessel 1, if it is under sufficient pressure, for example, its own vapour pressure, will thereupon be driven out from the chamber 5 through the outlet-pipe 6 and nozzle 7.

15 A suitable handle 12 is provided on the container 1 so that the whole device can be easily handled so as to direct the jet of liquid where it is required.

When it is required to provide some independent means for producing pressure on the liquid in the vessel 1, an arrangement similar to that illustrated may be used. Within the vessel 1 there is mounted a bracket 13 which constitutes a holder for a bulb 14 of the known type containing carbon-dioxide under high pressure. These bulbs are closed by a soft metal stopper or other device which can be easily ruptured, and the parts are so arranged that this bulb lies in the path of movement of the pin 8. In the operation of the device the pin 8 is forced inwards and it first punctures the diaphragm 3 and then further movement causes it to puncture or otherwise open the bulb 14 and release the compressed gas therefrom. This gas bubbles up through the liquid to the top of the chamber 1 and drives the liquid out through the ruptured diaphragm 3 into the chamber 5 and thence to the outlet-pipe 6.

It will be seen that this invention provides a fire-extinguishing device in which the fire-extinguishing liquid is contained in a truly hermetically-sealed vessel, and no valves, stop-cocks or special joints are required. The pin 8 may be a simple sliding fit in the bush 9, for this bush is not in contact with the liquid until such time as the fire-extinguisher is in use, and any slight leakage which might then take place is quite immaterial. The device is therefore inexpensive to manufacture and at the same time more reliable and satisfactory than other devices in which special arrangements of valves have to be used.

It will be appreciated that this invention is not limited to the particular construction hereinbefore described, for various other ar-

rangements can be used, for example for effecting the puncturing of the diaphragm 3 and the release of the compressed gas. Also, the actual construction of the container itself, the outlet pipe, and the nozzle, may be varied to suit any special requirements. These and other like modifications are all held to lie within the scope of the present invention as set forth in the appended claims.

I claim:

1. A fire extinguisher of the class described, comprising a casing divided into two chambers, one of said chambers constituting an hermetically sealed main liquid container or reservoir for fire extinguishing liquid and the other of said chambers being normally free from liquid and having an outlet nozzle, a part of the wall of the reservoir being openable by a striking pin, a striking pin arranged to open said part thereby releasing the liquid into the second chamber, and pressure generating means comprising a vessel set entirely within the reservoir and openable by the continued movement of the striking pin after it has opened said reservoir.

2. A fire extinguisher of the class described, comprising a casing divided by a puncturable diaphragm into two chambers, one of said chambers constituting an hermetically sealed vessel adapted to hold fire extinguishing liquid, the second chamber being normally free from liquid and having an outlet nozzle, a striking pin carried by the second chamber and arranged to puncture the diaphragm, and a compressed gas bulb having a rupturable stopper mounted entirely within said vessel, which stopper is so situated as to be opened by the continued movement of the striking pin after it has punctured said diaphragm.

3. A fire extinguisher of the class described comprising a casing divided by a puncturable transverse diaphragm into two chambers, one at each end of the casing, one of said chambers constituting an hermetically-sealed vessel adapted to hold fire extinguishing liquid and the second chamber having an outlet nozzle, a striking pin carried by the casing and arranged to puncture the diaphragm, and a pressure generating vessel situated entirely within said hermetically-sealed vessel and openable by the continued movement of the striking pin after it has punctured the diaphragm.

In testimony whereof I affix my signature.
HUGH GRIFFITHS.
